GARMENT HANGER

Otto Emile Hoehn, New Orleans, La.

Application March 29, 1935, Serial No. 13,765

1 Claim. (Cl. 223—88)

The present invention relates to new and useful improvements in garment hangers and has for its primary object to provide, in a manner as hereinafter set forth, a device of this character embodying a novel construction whereby trousers may be mounted thereon and left for any length of time without forming a crease therein.

Other objects of the invention are to provide a garment hanger which will be comparatively simple in construction, strong, durable, compact, light in weight, attractive in appearance and which may be manufactured at low cost.

All of the foregoing and still further objects and advantages of the invention will become apparent from a study of the following specification, taken in connection with the accompanying drawing wherein like characters of reference designate corresponding parts throughout the several views, and wherein:

20 Figure 1 is a perspective view of a garment hanger constructed in accordance with the present invention.

Figure 2 is a view in bottom plan of the invention.

25 Figure 3 is a view in vertical longitudinal section through a portion of the device.

Figure 4 is a perspective view of the outer end portion of one of the wire arms.

Referring now to the drawing in detail, it will be seen that the embodiment of the invention which has been illustrated comprises a pair of oppositely inclined arms 1, said arms 1 being formed from a single length of suitable wire having an intermediate portion bent in a manner to provide a supporting hook 2, and then twisted, as at 3, to provide the shank 4 of said hook 2. It will thus be seen that a hook comprising two wires is provided for added strength.

40 The inclined arms 1 terminate in turned outer

end portions 4 between which a supporting bar 5 of arcuate cross section extends, said bar 5 being of any suitable material, preferably metal. The bar 5 is fixed on the inturned end portions 4, as by spot-welding at 6.

5 It is thought that the manner of using the garment hanger will be readily apparent. Trousers are mounted on the bar 5, the construction and shape of which is such as to prevent forming the usual objectionable crease in said trousers. In addition, the bar 5 constitutes a rigid and durable brace between the outer ends of the wire arms 1.

10 It is believed that the many advantages of a garment hanger constructed in accordance with the present invention will be readily understood, and although a preferred embodiment of the invention is as illustrated and described, it is to be understood that changes in the details of construction and in the combination and arrangement of parts may be resorted to which will fall 15 within the scope of the invention as claimed.

20 What is claimed is:—

The herein described garment hanger comprising essentially a pair of oppositely inclined 25 arms formed of a single length of wire having at its middle a supporting hook of two thicknesses of wire and a shank of twisted wires, said arms terminating in inwardly extending aligned end portions, a supporting bar of arcuate cross section arranged endwise between the bights of the 30 said arms and superimposed on said inturned end portions of the arms, and spot-weldings fixedly connecting the said end portions of the arms and the supporting bar; said spot-weldings spaced inwardly from the ends of the bar and located at 35 intermediate points in the length of the inwardly extending end portions of the arms.

OTTO EMILE HOEHN. 40
